CLAIM

The ornamental design for a combined puzzle and holder therefor, as shown and described.

DESCRIPTION

FIG. 1 is a front perspective view of a combined puzzle and holder therefor showing our new design;
FIG. 2 is a front elevational view thereof;
FIG. 3 is a rear elevational view thereof;
FIG. 4 is a side elevational view thereof;
FIG. 5 is a top plan view thereof;
FIG. 6 is a perspective view of the design shown in FIGS. 1 through 5 in an open condition;
FIG. 7 is a end elevational view thereof;
FIG. 8 is a right side elevational view thereof;
FIG. 9 is a left side elevational view thereof;
FIG. 10 is a bottom plan view thereof;
FIG. 11 is a top plan view thereof;
FIG. 12 is a front elevational view thereof;
FIG. 13 is a rear elevational view thereof;
FIG. 14 is a left side elevational view thereof; and
FIG. 15 is a right side elevational view thereof;
